224,175

COSMETIC VANITY TRAY

Rebecca Mark, 195 Turn of River Road,
Stamford, Conn. 06905

Filed Oct. 12, 1970, Ser. No. 25,439

Term of patent 14 years

Int. Cl. D3—02

U.S. Cl. D86—10

FIG. 1 is a perspective view of a cosmetic vanity tray showing my new design;

FIG. 2 is a front elevational view thereof;

FIG. 3 is a top plan view thereof;

FIG. 4 is a rear elevational view thereof; and

FIG. 5 is an end elevational view thereof, the end opposite being identical thereto.

I claim:

The ornamental design for a cosmetic vanity tray, substantially as shown and described.
